UNITED STATES PATENT OFFICE.

HENRY V. WESCHE, OF LASQUETI ISLAND, BRITISH COLUMBIA, CANADA.

TOY BUILDING-BLOCKS.

1,286,462.

Specification of Letters Patent.

Patented Dec. 3, 1918.

Application filed May 21, 1918. Serial No. 235,844.

To all whom it may concern:

Be it known that I, HENRY V. WESCHE, subject of the King of Great Britain, resident of Lasqueti Island, in the Province of

5 British Columbia, Dominion of Canada, have invented certain new and useful Improvements in Toy Building-Blocks, of which the following is a specification.

This invention relates to toy building 10 structures, and has for one of its objects to provide a plurality of units of various lengths and sizes and adapted to be coupled whereby structures of various forms may be erected.

15 Another object of the invention is to provide a plurality of units of varying lengths and a plurality of coupling devices which may be applied to the units to enable them to be temporarily united to produce structures 20 of varying forms.

With these and other objects in view, the invention consists in certain novel features of construction, as hereinafter shown and described and then specifically pointed out 25 in the claims; and in the drawings illustrative of the preferred embodiment of the invention—

Figures 1 to 7 are perspective views of the various units whereby the various structures 30 may be erected.

Figs. 8 and 9 are perspective views of structures erected by the improved units, illustrating the adaptability of the device to the erection of structures of various forms.

35 Fig. 10 is a detail illustrating the manner of coupling two of the units.

Fig. 11 is a side elevation, partly in section, illustrating the manner of coupling a plurality of the units.

40 Fig. 12 is a perspective view of a portion of one of the constructing units with one of the coupling devices applied.

Fig. 13 represents various forms of the coupling devices.

45 Fig. 14 represents a canopy or roof shaped member which may be employed to illustrate a porch roof or the like.

Fig. 15 represents a panel unit adapted to be engaged with the other units.

50 The improved device includes a plurality of units of various lengths adapted to be coupled to form structures of various forms, the units being preferably of wood, thoroughly seasoned to prevent shrinkage by exposure. One of a set of the units is illus-

trated in Fig. 1, by the character 10, and is substantially square transversely with a pin receiving socket 11 in each end.

Another of the units is illustrated in Fig. 2 at 12, being oblong transversely. Each of the units 12 is provided with a plurality of pin receiving apertures 13 corresponding in area to the sockets 11. Another one of a set of units is illustrated in Fig. 3 at 16, and is similar to the units 12 except that it lacks 60 pin receiving apertures 13. A unit of another set is illustrated in Fig. 4 by the character 14, said unit corresponding transversely to the units 12 and being provided with beveled ends as shown at 15. Another 65 one of a set of the units is represented in Fig. 5 and designated by the character 17 with the tapered ends 15 and provided with pin receiving apertures 18. One or more of the units will likewise be formed as shown 70 in Fig. 6 by the character 19, with one side thereof reduced toward the center from each end, as shown at 20. All of the units except the units 10 are preferably oblong transversely, and each of the units is provided 75 with longitudinally directed channels 21 in their side faces. A plurality of pins, one of which is shown at 22 in Fig. 11 are provided and adapted to fit in the sockets 11 of the units 10 and pass through the apertures 13 80 or 18 of the units 12 or 17.

85 A plurality of coupling devices are provided to enable the various units to be detachably united to support the structure which is erected thereby in position. Each 90 of the coupling devices is formed from a strip of wire bent substantially into U-shape with the arms or sides 23 adapted to enter the channels 21 at the ends of a unit with the portion 24 between the arms extending beyond the unit in which it is supported as illustrated in Figs. 11, and 12, the extended portions of the coupling devices being adapted to enter the channels 21 of an adjacent unit and thus temporarily couple the units and hold 95 them in position. By providing a plurality of the various units of different lengths it will be obvious that various structures representing houses, churches, bridges, tables, chairs and the like may be erected by arranging the various units in position and coupling them by the devices illustrated in Fig. 13. For illustration in Fig. 8 a church-like structure is formed by coupling the various 100 units together, and it is obvious that the de- 105

110

tails may be altered to any required extent according to the taste of the child or person using the construction units. In Fig. 9 the representation of an arch or bridge is shown constructed from the units illustrated in Figs. 1 to 5.

A foundation member will likewise be provided as illustrated in Fig. 7. The foundation member comprises an oblong base or box 25 having a plurality of sockets 26 formed therein in spaced relation to receive the lower ends of a plurality of the pins 22. Foundation members of the like character are shown in Fig. 9, to illustrate the manner of using the same.

The improved device is simple in construction, and may be utilized to instruct and amuse children and to encourage and stimulate their imaginative and constructive characteristics.

In Fig. 14 a roof or canopy forming member is shown and designated by the character 27 with its upper edge 28 bent at 29 to enter one of the channels 21 or between a pair of the units, and with its ends 30 bent to enter the channels of adjacent units. The manner of employing the roof or canopy forming member is illustrated in Fig. 8.

A plurality of flat filler plates or panels 31 may likewise be employed and engaged by their edges in the channels 21, so as to cause the structure to present the appearance of having imperforate walls.

The intermediate portions 24 of the coupling devices which are employed in connection with the beveled terminals, 15, will be directed at an angle to the side portions 23, as shown in Fig. 13 to enable the beveled terminals to be coupled to the other units as illustrated at the left in Fig. 11.

Having thus described the invention, what is claimed as new is:

1. Toy structural material including a plurality of units substantially rectangular transversely and having sockets in the ends, a plurality of units substantially oblong transversely and having transverse apertures, a plurality of units substantially oblong transversely and having transverse apertures and beveled ends, each of said units having longitudinally directed channels in their side faces, a plurality of pins adapted to engage in said sockets and through said apertures, and a plurality of substantially U-shaped coupling devices supported by their legs in the channels of one unit and adapted to engage at the bend in the channel of an adjoining unit.

2. Toy structural material including a plurality of units having end sockets and longitudinally directed side channels, a plurality of units having longitudinally directed side channels and transverse apertures, a plurality of pins adapted to engage said sockets and apertures, and a plurality of

coupling devices in substantially U-shape with the sides adapted to engage in the channels at the ends of one of the units and with the intervening portion thereof adapted to engage in one of the side channels of another of the units.

3. Toy structural material including a plurality of units having longitudinally directed side channels, and a plurality of coupling devices in substantially U-shape with the sides adapted to engage in the channels at the ends of one of the units and with the intervening portions adapted to engage in one of the side channels of another of the units.

4. Toy structural material including a plurality of units having end sockets and longitudinally directed side channels, a plurality of units having longitudinally directed side channels and transverse apertures intersecting said side channels, pins adapted to engage said sockets and apertures, and a coupling member fitting in the longitudinal channels of one unit and engaging in one of the longitudinal channels of another unit.

5. Toy structural material including a plurality of units having sockets in their ends and provided with longitudinal channels, a plurality of units having transverse apertures, pins adapted to engage in said sockets and through said apertures, and a substantially U-shaped coupling member fitting within the longitudinal channels of one unit and adapted to engage the longitudinal channel of an adjacent unit.

6. Toy structural material including a foundation unit having spaced sockets therein, a plurality of units having sockets in their ends and provided with longitudinal channels, a plurality of units having longitudinally directed side channels and transverse apertures intersecting said side channels, pins adapted to fit in the sockets of the foundation unit and extend through said apertures, and a coupling member fitting within the longitudinal channels of one unit and adapted to engage the longitudinal channel of another unit.

7. Toy structural material including a plurality of units having end sockets and longitudinally directed side channels, a plurality of units having transverse apertures, pins adapted to engage in said sockets and through said apertures, and a canopy forming unit having a laterally extending edge adapted to fit in the longitudinal side channel of one of the units.

8. Toy structural material including a plurality of units having end sockets and longitudinally directed side channels, other units having longitudinal side channels and beveled ends and provided with transverse apertures, pins adapted to engage said sockets and apertures, and coupling devices fitting within the channels of the beveled units

and conforming to the shape of beveled ends of the said units and projecting within the longitudinal channels of the adjacent units.

9. Toy structural material including a plurality of interchangeable units, each provided with longitudinally directed channels, certain of the units being provided with end sockets and others with transverse apertures, pins seated in said sockets and extending through the apertures, and coupling devices fitting in the channels of certain of the units and adapted to enter the channels of adjacent units.

10. Toy structural material including a plurality of elongated interchangeable units,

each provided with longitudinally directed side channels, certain of the units having sockets formed in the ends thereof, others being provided with transverse apertures and still others with oppositely disposed beveled ends, pins seated in the sockets and extending through the transverse apertures, and coupling devices seated in the channels of the units and provided with intermediate portions extending across the adjacent ends of said units and adapted to fit in the channel of an adjacent unit when said units are assembled to form a structure.

In testimony whereof I affix my signature.

HENRY V. WESCHE. [L. s.]
